WEATHER STRIP MECHANISM

Louis S. Pedersen, Chicago, Ill.

Application February 29, 1932. Serial No. 595,825

1 Claim. (Cl. 20—68)

This invention relates to windows and more particularly to storm plates therefor, although certain features thereof may be employed with equal advantage for other purposes.

5 It contemplates more especially the provision of more simple and improved means for manipulating storm plates for window structures so as to preclude the entrance of foreign substances and climatic exposure. Numerous types of storm 10 plate operating mechanisms have heretofore been proposed but these are too intricate and expensive in construction as well as installation to warrant the general adoption thereof as standard equipment. Devices of this character 15 must be simple, dependable and entail little labor in the installation thereof in order to render such commercially practical. It is manifest that simplicity of construction and dependable operation must be attended with minimum wear on 20 the moving elements thereof.

One object of the present invention is to simplify the construction and improve the operation of the device of the character mentioned.

25 Another object is to provide improved means for manipulating storm plates for window structures.

Still another object is to provide simple means for affording the attachment of the storm plate 30 operating mechanism to window frames now in use.

A further object is to provide a simple expedient for operating window storm plates without 35 entailing much labor or time in the installation thereof.

A still further object is the provision of a simple, inexpensive and positive operating mechanism for storm plates and similar devices.

40 Other objects and advantages will appear from the following description of an illustrative embodiment of the present invention.

In the drawing:

Figure 1 is a sectional view in elevation of a window structure equipped with a storm plate 45 operator embodying features of the present invention.

Figure 2 is a sectional view taken substantially along line II—II of Figure 1.

Figure 3 is an interior front view of a window 50 structure showing the storm plate operative attachment.

Figure 4 is a side view in elevation of the storm plate operator spindle shown assembled in Figure 1.

55 Figure 5 is a front view in elevation of sec-

tional plates constituting the retainer member for the operator mechanism.

The structure selected for illustration comprises a window frame 10 of standard or approved construction with the stiles 11 thereof properly fitted for receiving the customary window sash 12. The window sash 12 is maintained within the stiles 11 for pivotal displacement owing to the retaining hinge members 14 screwed or otherwise attached to one edge of 60 the stiles 11. As shown, the window sash 12 is provided with transparent window panes 15 to serve as a closure therefor in accordance with modern and standard practice.

The window sash 12 pivots inwardly to pass 70 over the sill 16 which has an inclined shoulder 17 formed thereon to define an exterior ledge precluding or at least minimizing the admission of the passing of foreign substances for entrance to the building structure.

75 It is apparent, however, that the required pivoting of the window sash 12 inwardly does not ordinarily afford any positive barrier for foreign substances to find entrance. In order to provide a positive barrier, a storm plate 18 is disposed within a groove 19 milled in the bottom member 20 of the window sash 10 for the entire length thereof. To this end, the storm plate 18 has a bottom region thereof provided with an inclined surface 21 complementary 80 to and corresponding with the similarly inclined ledge 17 provided along the bottom region of the window frame 10. Consequently, the storm plate 18 serves as a positive barrier precluding transmission between the interior and exterior 85 of the building structure through a medium of a crevice required for allowing the window sash 12 to open and close by pivoting along a side edge thereof by reason of the hinges 14. Any 90 number of hinges may be employed to support the window frame 12, and this may be varied by the requirements and dictates of commercial practice.

95 In order to manipulate the storm plate 18 so that the window sash 12 may be pivoted inwardly without obstruction of the ledge 17, simple manual means are provided for that purpose. To this end, a circular bore 22 is provided in the bottom member 20 of the window sash 12, and a spindle 23 inserted therein for operative connection with the storm plate 18. In the present embodiment, displacement of the storm plate 18 responsive to the spindle 23 is accomplished by virtue of an eccentric 24 secured on the spindle 23 proximate to one end thereof which 100

has an extremity 25 reduced in diameter for registry with a correspondingly shaped bore 26 serving as a bearing therefor. It is to be noted that the bearing bore 26 communicates with 5 groove 19 but does not have any exterior exposure by reason of its failure to extend through the bottom member 20 of the window sash 12. This is readily provided therein owing to the access afforded by the spindle bore 22, and the 10 spindle eccentric or cam 24 is received there-through for registry with an appropriately shaped aperture 26 provided in the storm plate 18. In consequence thereof, rotation of the spindle 23 will elevate and lower the storm plate 18 by positive action to enable the pivotal movement of the window sash 12 or to serve as a barrier against the entrance of foreign substances and obviating climatic exposure.

The spindle 23 is maintained in position and 20 the extremity 25 thereof retained in the bearing 26 by virtue of sectional plates 27 and 28 which have the adjacent edges 29 thereof provided with semi-circular complemental notches 30 and 31, respectively. The semi-circular notches 30 and 31 register with an annular groove 32 provided in the spindle 23, thereby retaining the latter in operative position against longitudinal or axial movement responsive to attachment of the plates 27 and 28 to the window 25 sash 12 in concealment of the bore 22 provided in the bottom member 20 thereof.

Any suitable fasteners such as wood screws 33 may be utilized to effect the attachment of 30 the plates 27 and 28 to the interior surface of the window sash bottom member 20 in the position described supra. The storm plate 18 is 35 preferably provided with inclined top edges 35 so as to avoid engagement with the mortise joint which connects the side and bottom members 40 constituting the window sash 12. Lateral displacement of the storm plate 18 is prevented by the pins 36 fastened in the sash member 20 and passing through vertical slots 37 in the storm plate 18 which provides registry therewith. The slots 37 serve to limit the vertical 45 displacement of the storm plate 18. It is apparent, therefore, that very simple and effective mechanism has been provided to manipulate the

storm plate 18 for positive upward and downward movement responsive to turning the knob 34 provided on the interior extremity of the spindle 23. The knob 34 is preferably knurled to enable the convenient and positive manipulation thereof. 80

With the arrangement above described, it is apparently a very novel, inexpensive and dependable operating mechanism that has been provided for storm plates. These may be attached to windows of standard construction without inconvenience or entailing much labor or expense, since the provision of round bores and apertures is very easily accomplished with nominal installation expense. Any number of 85 operators 23 may be provided in a single window sash depending upon the dictates of commercial practice, and it is apparent that the elongated aperture 26 allows the cam 24 to idle 90 therein so that vertical displacement of the storm plate 18 is only effected, thereby avoiding tilting of the storm plate 18, there being a requirement for some side allowance to afford the elevation and lowering of the storm plate 95 through the medium of the eccentric 24. 100

Various changes may be made in the embodiment of the invention herein specifically described without departing from or sacrificing any of the advantages of the invention as defined in the appended claim. 105

I claim:

The combination with a sash or frame, of a storm plate movably associated with said sash or frame for extension therefrom, there being a closed end bore in said sash or frame for communication with said plate, a shaft freely extending in said bore, means on the extremity of said shaft for journaled support in the closed end of said bore, said shaft being in operative connection with said storm plate to effect the reciprocation thereof responsive to rotating said shaft, there being an annular groove on said shaft, and a sectional bracket plate attached to said sash or frame in operative connection with said shaft groove to preclude the longitudinal displacement thereof and conceal said bore. 115 120 125
